DESIGN FOR A NAVIGATING BRIDGE OR SIMILAR STRUCTURE

Norman Bel Geddes, New York, N. Y.

Application November 1, 1933, Serial No. 49,619

Term of patent 14 years

To all whom it may concern:

Be it known that I, NORMAN BEL GEDDES, a citizen of the United States, residing in the Borough of Manhattan, city, county, and State of New York, have invented a certain new, original and ornamental Design for a Navigating Bridge or Similar Structure, of which the following is a specification, reference being had to the accompanying drawing forming a part thereof, in which—

Figure 1 is a perspective view of a navigating bridge or similar structure embodying my design,

the structure being viewed from a point forward and to one side thereof, and somewhat above the same; and

Fig. 2 is a perspective view thereof, taken from the side.

I claim:

The ornamental design for a navigating bridge or similar structure substantially as shown.

Signed this 25 day of October, 1933.

NORMAN BEL GEDDES.
